UNITED STATES PATENT OFFICE.

ADOLPH DIECKMANN, OF CINCINNATI, OHIO.

MECHANISM FOR FORMING SHEET-METAL ELBOWS.

1,010,733.

Specification of Letters Patent.

Patented Dec. 5, 1911.

Application filed January 18, 1906. Serial No. 296,594.

To all whom it may concern:

Be it known that I, ADOLPH DIECKMANN, a citizen of the United States, residing at Cincinnati, in the county of Hamilton and State of Ohio, have invented certain new and useful Improvements in Mechanism for Forming Sheet-Metal Elbows, of which the following is a specification.

My invention relates to improvements in mechanism for forming sheet metal elbows.

One of its objects is to provide improved mechanism for clamping and shaping the elbow blank.

Another object is to provide improved means for pressing down the crimps.

Another object is to provide improved mechanism for actuating the above mentioned devices.

It further consists in certain details of form, combination and arrangement, all of which will be more fully set forth in the description of the accompanying drawings, in which;

Figure 1 is a central vertical longitudinal section through my improved mechanism. Fig. 2 is a section on line $\alpha-\alpha$ of Fig. 1, showing one of the clamping and shaping mechanisms in plan view. Fig. 3 is a plan or end view of the other or movable clamping and shaping mechanism. Fig. 4 is a plan view of the crimp forming mechanism. Fig. 5 is a side elevation of the mandrel detached. Fig. 6 is a central vertical section through a modified clamping and shaping mechanism.

In the accompanying drawings A represents a frame or base having an arm A' to which is secured a hollow mandrel B. The forward end of this mandrel is corrugated at B' or otherwise shaped to correspond to the outline or shape to be imparted to the elbow. The sheet metal or blank from which the elbow is to be formed is first formed into a cylinder C with overlapping edges, which cylinder or tube is slipped over the mandrel. The inner edge of the tube rests against a ring c by means of which the tube is fed forward on the mandrel after each radial crimp is formed.

D represents a ring or frame supported by the base and encircling the forward or free end of the mandrel. Projecting inward from ring D are a series of presser feet or clamping jaws E, which as shown in Figs. 1 and 2 are attached by slots e and guides d to ring D, and are moved toward and from

the mandrel by means of links F G pivoted to the feet and ring respectively at g f, said links being pivoted to each other by pins f'. Rings H H' are clamped together by screws h and move together relative to ring D, journaling on the inner face thereof. The pins f' also engage slotted openings h' in rings H H' so that movement of rings H H' relative to ring D serves to bring the centers f f' g into line, thereby forcing the feet against the mandrel, or by movement in the opposite direction, to move the feet away from the mandrel. Fig. 2 shows the feet clamped upon the mandrel and Fig. 3 shows the position of the parts when they are retracted.

I represents a worm which may be turned by a hand lever J or otherwise operated, and K a segment of a worm wheel carried by ring H to engage and be driven by said worm. The feet E serve to clamp the cylinder to the end of the mandrel and to cause it to conform to the shape of the mandrel.

A ring L similar to ring D is pivoted to ring D by means of ears l l. Ring L is provided with a series of feet M similar to feet E, which are operated by links F' G', rings H' H'', segment K' and worm m, in the same manner as the feet E. The feet M clamp the blank C upon a core or secondary mandrel N of the same external outline as the forward end of mandrel B. Core N is held in place relative to the mandrel by a projecting tongue n seating in a recess therein. Between the core N and the end of the mandrel is a crimp former Q composed of a series of sections o, the upper and side sections of which may be moved outwardly as indicated in Figs. 1 and 4 by means of a polygonal wedge P carried by rod p. The expanding of sections o serves to form a radial crimp Q in the blank C between the ring or core N and the end of the mandrel, said crimp being of greater depth at the top. The sections o are held together by ring O' to which they are secured by screws passing through slotted openings.

Rod p may be shifted by means of a hand lever p' pivoted at p' to the rear end of the mandrel, and to which rod p is attached. After the sections o have formed crimp Q and have been retracted the parts M N are shifted on center l' causing the inclined faces e' m' of feet E M to press the faces g' q' of crimp Q together between said inclined faces, thereby closing up said crimp

and forming a fractional bend or curvature of the blank, due to the metal taken up on one side to form the crimp. The feet E M are then retracted and the blank C fed forward on the mandrel to a point where it is desired to form the next crimp. When the feet M again clamp the blank, the last formed crimp is forced down thereby upon the face of the blank as indicated in Fig. 1.

10 If the shanks C' of the elbow are long enough to require it, the feet E are pressed thereon to give them the same cross sectional pattern as the body of the elbow, so that the elbow will have the same pattern throughout out. The lower section o of the crimp former rests on the tongue n of the mandrel.

In the modification Fig. 6 the respective feet 2 are supported in a ring or frame 3 by means of pistons or plungers 4 working in 20 cylinders 5 formed in said frame. The feet are clamped upon the blank and retracted by means of fluid pressure. 6 and 7 represent ports leading to opposite ends of the respective cylinders from a two way cock 25 8, which may be turned to admit fluid pressure to either end of the several cylinders, and to exhaust from the opposite end of said cylinders. 9 represents the mandrel, 10 the blank clamped thereon, and 11 piston rods connecting the feet with the plungers. 30 A single two way cock may be employed to operate both series of feet.

The number of feet may be varied as required by the pattern of the mandrel or 35 other considerations. In Fig. 2 I have shown eight feet and in Fig. 6 only four. With the mechanism herein shown I am enabled to form the radial crimps and the cross sectional pattern at a single operation.

40 The mechanism herein shown is capable of considerable modification without departing from the principle of my invention.

Having described my invention, what I claim is;

45 1. In a mechanism of the character indicated, a mandrel, a frame encircling the free end of said mandrel, a crimp former at the end of said mandrel, and a series of feet carried by said frame and adapted to be 50 projected against and retracted from said mandrel to clamp the elbow blank to the mandrel during the formation of the crimp.

55 2. In a mechanism of the character indicated, a mandrel, a crimp former at the free end of said mandrel, a frame encircling the free end of said mandrel, a series of feet carried by said frame and adapted to be 60 projected against and retracted from said mandrel to clamp the elbow blank to the mandrel during the formation of the crimp, and means for simultaneously actuating said feet.

65 3. In a mechanism of the character indicated, a mandrel, having an irregular exterior of the pattern to be imparted to the

elbow, a crimp former at the free end of said mandrel, a frame encircling the free end of said mandrel, a series of feet carried by said frame and adapted to be projected against and retracted from said mandrel to clamp the elbow blank to the mandrel during the formation of the crimp. 70

4. In a mechanism of the character indicated, a mandrel, a crimp former located at the free end of said mandrel, a secondary movable mandrel located on the opposite side of said crimp former, frames encircling said mandrel and secondary mandrel, one of said frames moving pivotally relative to the other, a series of feet projecting inwardly from each of said frames to clamp the elbow blank respectively to the mandrel and secondary mandrel, and means for simultaneously actuating the respective series of feet. 75

5. In a mechanism of the character indicated, a mandrel having an exterior of the pattern which it is desired to impart to the elbow, a crimp former at the free end of said mandrel, a series of feet supported about said mandrel by a frame, said feet having inclined faces at the end adjacent to the crimp former, and their faces adjacent to the mandrel fitted to the pattern thereof, and means for simultaneously actuating 90 said feet. 95

6. In a mechanism of the character indicated, a mandrel, a crimp former at the free end of said mandrel, a frame encircling the free end of said mandrel, a series of feet connected to said frame by links, a ring journaled and adapted to move relative to said frame, and connections between said ring and the links of the respective feet, whereby the movements of the ring serve to 100 simultaneously actuate the several feet. 105

7. In a mechanism of the character indicated, a mandrel, a crimp former at the free end of said mandrel, a frame encircling the free end of said mandrel, a series of feet connected to said frame by links, a ring journaled and adapted to move relative to said frame, connections between said ring and the links of the respective feet, a worm carried by said frame, and a worm-wheel segment carried by said ring in mesh with 110 said worm. 115

8. In a mechanism of the character indicated, a mandrel, a crimp former at the free end of said mandrel, a secondary movable 120 mandrel located on the opposite side of said crimp former, frames encircling said mandrel and secondary mandrel, one of said frames moving pivotally relative to the other, separate series of feet projecting inwardly from each of said frames to clamp the elbow blank respectively to the mandrel and secondary mandrel, links connecting said several feet to the respective frames, rings journaled relative to said 125 130

frames and connected to said links so that the movement of said rings serves to simultaneously actuate the feet attached to the respective frames.

- 5 9. In a mechanism of the character indicated, a mandrel, a crimp former at the free end of said mandrel, a series of feet movable in a radial direction to and from said mandrel to clamp the blank thereto, a secondary 70
10 movable mandrel located on the opposite side of said crimp former, the exterior of said secondary mandrel being the same that is to be imparted to the elbow, and a series of feet movable in a radial direction to and 75
15 from said secondary mandrel to lay down the crimps and shape the crimped portion of the elbow to the pattern of said secondary mandrel.

10. In a mechanism of the character indicated, a mandrel, a crimp former at the free 20 end of said mandrel, a series of feet movable in a radial direction to and from said mandrel to clamp the blank thereto, a detachable secondary movable mandrel located 25 on the opposite side of said crimp former, the exterior of said secondary mandrel being the same that is to be imparted to the elbow, and a series of feet movable in a radial direction to and from said secondary 30 mandrel to lay down the crimps and shape the crimped portion of the elbow to the pattern of said secondary mandrel.

11. In a machine for making sheet metal pipe elbows the combination of a stationary 35 corrugated die, a correspondingly corrugated swinging die, radially movable bulging dies, means for projecting said bulging dies outwardly between the stationary and swinging dies when they are separated, dies 40 surrounding the stationary and swinging dies and fitting the corrugations therein, the dies surrounding the swinging die being movable radially toward and from the same and capable of swinging therewith toward 45 and from the stationary die, means for moving the dies surrounding the swinging die radially, and means for moving the swinging die with the associated surrounding dies toward the stationary die when the bulging 50 dies are withdrawn inward, substantially as described.

12. In a machine for making sheet metal pipe elbows the combination of a stationary corrugated die, a correspondingly corrugated 55 swinging die pivotally connected therewith adjacent to one side and movable toward and from the same on the opposite side, radially movable bulging dies, means for projecting said bulging dies outwardly 60 between the stationary and swinging dies when they are separated, dies surrounding the stationary and swinging dies and fitting the corrugations therein, their opposing faces adjacent to the bulging dies being correspondingly beveled and the dies surround- 65

ing the swinging die being movable radially toward and from the same and capable of swinging therewith toward and from the stationary die, means for moving the dies surrounding the swinging die radially, and 70 means for moving the swinging die with the associated surrounding dies toward the stationary die when the bulging dies are withdrawn inward, substantially as described.

13. In a machine for making sheet metal pipe elbows the combination of a hollow stationary corrugated die, a correspondingly corrugated wedge shaped swinging die pivotally connected adjacent to its thicker side with the stationary die, longitudinally and 75 radially movable bulging dies mounted in said hollow die, means for projecting said bulging dies outwardly between the stationary and swinging dies when they are separated, dies surrounding the stationary and swinging dies and fitting the corrugations 80 therein, their opposing faces adjacent to the bulging dies being correspondingly beveled and the dies surrounding the swinging die being movable radially toward and from the 85 same and capable of swinging therewith toward and from the stationary die, means for moving the dies surrounding the swinging die radially, and means for moving the swinging die with the associated surrounding 90 dies toward the stationary die when the bulging dies are withdrawn into it, substantially as described.

14. In a machine for making corrugated elbows, the combination of means for progressively forming longitudinal corrugations in a pipe section, means for successively pressing transverse bulges at intervals in one side of the corrugated part of the pipe, and means for closing said bulges and curving the pipe into elbow shape, substantially 100 as described.

15. In a machine for making corrugated elbows the combination of means for progressively forming longitudinal corrugations in a pipe section, means for successively pressing transverse bulges at intervals in one side of the pipe, means for closing said bulges and curving the pipe into elbow shape and means for folding the plaits 110 thus formed back against the pipe, substantially as described.

16. In a machine for making corrugated elbows the combination of corrugating heads or dies arranged one within the other, means 120 for feeding a pipe section step by step between said heads, a pivoted head movable toward and from the corrugating heads and provided with radially movable jaws, connections for operating said pivoted head and its jaws, bulging dies movable radially out and in between the free side of the pivoted head and the inner corrugating head, and means for operating said bulging dies, substantially as described. 125 130

17. In a machine for making corrugated elbows the combination of corrugating heads or dies arranged one within the other, means for feeding a pipe section step by step between said heads; a pivoted head movable toward and from the corrugating heads and provided with radially movable jaws; a clamping die pivoted to the inner corrugating head within the opening of the pivoted head, connections for operating said pivoted head, jaws and die; radially movable bulging dies, and means for intermittently moving said bulging dies outwardly between and beyond the clamping die and inner corrugating head, substantially as described.

18. In a machine for making corrugated elbows the combination of corrugating heads arranged one within the other, the outer head being provided with radially movable dies, means for moving said dies in and out, means for feeding a pipe section intermittently step by step between said heads when said dies are closed, a pivoted head adapted to swing toward and from the corrugating heads and provided with radially movable jaws, connections for operating said pivoted head and jaws, radially movable bulging dies between the inner corrugating head and the pivoted head, and means for intermittently thrusting said dies outward beyond the inner corrugating head, substantially as described.

19. In a machine for making corrugated elbows, the combination of inner and outer corrugating heads, means for feeding a pipe section intermittently step by step between said heads, a swinging head at the delivery side of the corrugating heads provided with an inner clamping die and with radially movable jaws, means for intermittently moving said jaws in and out toward and from the clamping die, radially movable bulging dies carried by the inner corrugating head, and a head movable axially within the inner corrugating head and adapted when moved in opposite directions to project and withdraw said bulging dies, substantially as described.

20. In a machine for making corrugated elbows, the combination of corrugating heads arranged one within the other, the outer corrugating head having radially movable dies and the dies on one side of said head having beveled ends, means for inter-

mittently feeding a pipe section between 55 said heads, a pivoted head movable toward and from the corrugating heads and provided with radially movable jaws, the jaws on one side of said head having their ends beveled in the same direction as the opposing beveled ends of the dies of the outer corrugating head, means for intermittently moving said jaws in and out, radially movable bulging dies carried by the inner corrugating head, means for intermittently projecting 60 said dies between the opposing beveled ends of the corrugating dies and jaws, and means for swinging the pivoted head toward the corrugating heads when the bulging dies are withdrawn, substantially as described.

21. In a machine for making corrugated elbows the combination of a mandrel terminating at its free end in a corrugating die, a stationary head surrounding said die and 75 provided with radially movable corrugating dies, means for moving the outer dies toward and from the inner fixed die, means for feeding a pipe on said mandrel step by step between said corrugating dies, a wedge 80 shaped clamping die pivoted on the thicker side to the fixed corrugating die and having its curved face correspondingly corrugated, a pivoted head arranged to swing toward and from said stationary head and provided 85 with jaws movable radially toward and from said clamping die and having correspondingly shaped faces opposed thereto, means for intermittently swinging said clamping die and pivoted head toward and from the 90 corrugating dies, radially movable bulging dies of gradually diminishing thickness from the narrower toward the thicker side of the clamping die, and means for intermittently projecting said bulging dies 95 between the clamping die and fixed corrugating die, the opposing ends of the movable corrugating dies and of the clamping jaws adjacent to the bulging dies being beveled or inclined outwardly toward the stationary 100 corrugating head, substantially as described.

In testimony whereof I have affixed my signature in presence of two witnesses.

ADOLPH DIECKMANN.
